UNITED STATES PATENT OFFICE.

RICHARD C. JENKINSON, OF NEWARK, NEW JERSEY, ASSIGNOR TO THE COE MANUFACTURING COMPANY, OF NEW JERSEY.

DESIGN FOR A TOE-CLIP.

SPECIFICATION forming part of Design No. 32,583, dated April 24, 1900.

Application filed March 5, 1900. Serial No. 7,421. Term of patent 7 years.

To all whom it may concern:

Be it known that I, RICHARD C. JENKINSON, a citizen of the United States of America, and a resident of Newark, in the county of Essex and State of New Jersey, have invented and produced a new and original Design for Toe-Clips, of which the following is a specification.

I will describe a toe-clip embodying my design.

10 In the accompanying drawings, which illustrate a toe-clip embodying my design, Figure 1 is a side elevation; Fig. 2, an end view, and Fig. 3 a top view.

15 The leading or essential feature of my design is the top or upper portion of the toe-clip.

Referring to the drawings, A represents a vertical portion, and $\alpha\alpha$ two flat bands or strips which extend at right angles to the portion A for a short distance and are then curved, 20 as shown at α' , in order that they may extend backward and overlie their under portions. For convenience I have designated the upper portions or top by the letters $\alpha^2\alpha^2$. The lower portions $\alpha\alpha$ extend in divergent directions,

while the upper portions $\alpha^2\alpha^2$ extend in convergent directions from the curves α' , and they are also substantially parallel with the lower portions $\alpha\alpha$. At about the end of their convergence they are connected by a strip α^3 , and from this strip they flare outwardly and 25 forwardly and are joined to the loops α^4 . The strip α^3 has a central portion α^6 , which projects into the space between the strip α^3 and a bar α^5 . The loops α^4 are also joined to the bar α^5 , the edges of which are substantially 30 straight. The bar α^5 is curved in the direction of its length, so as to have the loops α^4 beneath the horizontal plane of the upper portions $\alpha^2\alpha^2$.

What I claim is—

40 The design for a toe-clip substantially as shown and described.

Signed by me at Newark, New Jersey, this 15th day of February, 1900.

RICHARD C. JENKINSON.
